UNITED STATES PATENT OFFICE.

ALBERT W. HULL, OF SCHENECTADY, NEW YORK, ASSIGNOR TO GENERAL ELECTRIC COMPANY, A CORPORATION OF NEW YORK.

SYSTEM FOR PRODUCING OSCILLATIONS

Application filed May 18, 1921. Serial No. 470,723.

To all whom it may concern:

Be it known that I, ALBERT W. HULL, a citizen of the United States, residing at Schenectady, in the county of Schenectady, State of New York, have invented certain new and useful Improvements in Systems for Producing Oscillations, of which the following is a specification.

My present invention relates to a system for producing oscillating currents in which an electron discharge device having a negative resistance characteristic is employed.

In my prior U. S. Patent No. 1,313,188, of August 12, 1919, I have described a system for producing alternating currents in which the generation of oscillations is carried out by means of an electron discharge device which is so arranged as to have a negative resistance characteristic. This device consists essentially of an electron emitting cathode and two other electrodes enclosed in an evacuated receptacle. The system is so arranged that secondary electrons are emitted from one of the other electrodes to such an extent that the resistance between the cathode and the electrode from which secondary electrons are emitted is negative. If a resonant circuit is connected between the cathode and this electrode oscillations will be produced in this circuit and these oscillations may be supplied from the circuit in which they are produced to a circuit in which they are to be utilized. In the system described in my patent the electrode by which the secondary electrons are received is maintained at a constant positive potential. I have now discovered that it is not essential that the potential of the electrode which receives the secondary electrons be maintained constant. As a result I have found that it is possible to supply oscillations from the circuit between the cathode and the electrode which receives secondary electrons to a work circuit, and thereby greatly increase the efficiency of operation of the system. The operation of this system under these conditions is somewhat similar to that of a three-electrode or triode amplifier in which the grid is excited by means of an oscillating current and a greatly amplified alternating current is supplied from the plate circuit. My present system, however, differs in its operation from that of an ordinary amplifier in that the grid excitation is provided by the oper-

ation of the device itself and no separate source of energy is required for exciting the grid. In so far as the operation of the device with respect to the production of oscillations is concerned, my system differs from that of the usual three-electrode oscillators previously employed in that oscillations are produced in one of the circuits independently of any coupling between the circuits between the cathode and the other two electrodes.

The novel features which I believe to be characteristic of my invention are set forth with particularly in the appended claims. My invention itself, however, both as to its organization and method of operation will best be understood by reference to the following description taken in connection with the accompanying drawing in which Fig. 1 shows diagrammatically a simple circuit connection whereby my invention may be carried into effect, and Fig. 2 is a characteristic curve showing the relation between the potential of the electrode which emits secondary electrons and the current flowing in the circuit of said electrode.

As indicated in the drawing, I provide an electron discharge device 1 having an electron emitting cathode 2, an anode 3 and a grid electrode 4 interposed between cathode and anode. A circuit between the cathode and grid electrode includes the inductance 5 and capacity 6 by means of which this circuit may be tuned to the frequency of the oscillations which it is desired to produce. The circuit between cathode and anode includes a source of potential such as a battery 7 and a primary winding 8 of a transformer, the secondary 9 of which is included in the work circuit which in the case illustrated is made up by the antenna 10 of a radio transmitting system.

The connection from the grid to the cathode may be made by means of the variable connection 11 to a point in the battery 7 which is so chosen that a positive potential will be impressed upon the grid 4 of the right value to cause oscillations to be produced in the circuit between cathode and grid by reason of the negative resistance of that circuit as indicated in the curve of Fig. 2. When oscillations are produced in the grid circuit the potential of the grid will become alternately positive and negative with respect to the cathode, and the

current flowing between cathode and anode will be varied in accordance with the potential variations of the grid. By reason of the fact that the plate circuit includes a load the potential of the anode 3 will vary in accordance with the drop of potential through the load. The only essential for continuous operation of the system is that the potential of the source 7 shall be high enough so that the potential of the anode 3 will always be enough higher than that of the grid 4 to carry off the secondary electrons emitted from the grid 4.

In the system shown in my prior patent referred to above, the efficiency of operation depends upon the proper adjustment of the relations between the constants of the oscillating circuit and the load circuit associated therewith. In the present case since the oscillating circuit has to supply only the current necessary for varying the grid potential and is not coupled to the other circuit, the adjustment of this circuit is entirely independent of the adjustment of the load circuit, and since the energy in the oscillating circuit is but a small part of the total energy of the system the efficiency of operation of the oscillating circuit may be comparatively low without materially affecting the total efficiency of the system.

The frequency of the oscillations produced is fixed entirely by the tuning of the resonant grid circuit and is essentially independent of the tuning of the plate and load circuits. In this respect my improved system offers material advantages over the previously employed three-electrode oscillators in which the grid and plate circuits are coupled together and the plate circuit is in turn coupled to the load circuit, the frequency of the oscillations in this case being dependent to a large extent upon the tuning of the load circuit.

While I have shown and described the preferred embodiment of my invention, it will be apparent that my invention is by no means limited to the particular circuit connections and apparatus shown, but that many modifications therein may be made without departing from the scope of my invention as set forth in the appended claims.

What I claim as new and desire to secure by Letters Patent of the United States, is:—

1. The combination in a system for producing oscillating currents of an electron discharge device having a cathode, an anode and a grid, grid and plate circuits associated therewith, means for producing an emission of secondary electrons from said grid sufficient to produce a negative resistance characteristic in the grid circuit over a range of positive grid potential and thereby causing the generation of oscillations in said grid circuit independently of

any coupling between the circuits and a work circuit associated with said plate circuit.

2. The combination in a system for producing oscillating currents of an electron discharge device having a cathode, an anode and a grid, grid and plate circuits associated therewith, means for producing a negative resistance characteristic in said grid circuit over a range of positive grid potential by reason of the emission of secondary electrons from said grid and thereby causing the generation of oscillations in said grid circuit independently of any coupling between the circuits and a work circuit associated with said plate circuit.

3. The combination in a system for producing oscillating currents of an electron discharge device having a cathode, an anode and a grid, a resonant circuit connected between said cathode and grid which is tuned to the frequency of the currents to be produced, a plate circuit connected between said cathode and anode, means for producing a negative resistance characteristic in said grid circuit over a range of positive grid potential by reason of the emission of secondary electrons from said grid and a work circuit associated with said plate circuit.

4. The combination in a system for producing oscillating currents of an electron discharge device having a cathode and an anode, and a grid interposed between said cathode and anode, a resonant grid circuit connected between said cathode and grid which includes an inductance and a capacity, a plate circuit connected between said cathode and anode, a source of potential in said plate circuit and a work circuit coupled to said plate circuit, the device being so constructed and the potential in said plate circuit being so chosen that a negative resistance characteristic will be produced in said grid circuit over a range of positive grid potential by reason of the emission of secondary electrons from said grid whereby oscillations will be produced independently of any coupling between the circuits.

5. The method of operating a generating system comprising an electron discharge device having an electron emitting cathode, an anode and a grid and plate and grid circuits associated therewith which consists in producing an emission of secondary electrons from said grid sufficient to produce a negative resistance characteristic in said grid circuit over a range of positive grid potential, producing oscillations in said grid circuit independently of any coupling between the circuits and supplying oscillations from the plate circuit to a work circuit.

6. The method of operating a generating system comprising an electron discharge de-

vice having an electron emitting cathode, two other electrodes, and separate circuits connected between the cathode and each of the other electrodes which consists in producing an emission of secondary electrons from one of said electrodes sufficient to produce a negative resistance characteristic in the circuit connected thereto over a range of positive potential of the electrode connected to said circuit, producing oscillations in said circuit independently of any coupling between the circuit, and supplying oscillations from the other circuit to a work circuit.

7. The combination in a system for producing oscillating currents of an electron discharge device having a cathode and two other electrodes, separate circuits connecting the cathode with each of the other electrodes, means for producing an emission of secondary electrons from one of the said electrodes sufficient to produce a negative resistance characteristic in the circuit connected thereto over a range of positive potential of said electrode, and thereby causing the generation of oscillations in the circuit connected to said electrode independently of any coupling between the circuits and a work circuit coupled to the circuit which is connected to the other electrode.

8. The combination in a system for producing oscillating currents of an electron

discharge device having a cathode and two other electrodes, separate circuits connecting the cathode with each of the other electrodes, means for producing a negative resistance characteristic in one of said circuits over a range of positive potential of the electrode connected thereto by reason of the emission of secondary electrons from the electrode to which the circuit is connected and thereby causing the generation of oscillations in said circuit independently of any coupling between the circuits and a work circuit coupled to the other circuit.

9. The combination in a system for producing oscillating currents of an electron discharge device having a cathode and two electrodes, separate circuits connecting the cathode to each of the other electrodes, one of said circuits being resonant to the frequency of the currents to be produced, means for producing a negative resistance characteristic in said resonant circuit over a range of positive potential of the electrode connected thereto by reason of the emission of secondary electrons from the electrode to which said circuit is connected, and a work circuit coupled to the circuit of the other electrode.

In witness whereof, I have hereunto set my hand this 17th day of May, 1921.

ALBERT W. HULL.
